UNITED STATES PATENT OFFICE.

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK.

SLICING MACHINE.

REISSUED

Application filed March 10, 1928. Serial No. 280,726.

My invention relates to a slicing machine of the type having a rotary knife. One object of my invention is to provide an improvement in carriages for use with such a slicing machine, whereby the material to be sliced is passed across the face of the knife and into contact with the cutting edge thereof. Another object is the provision of such a carriage in which the work engaging member proper shall be pivoted upon said carriage for adjustment to various positions. Another object is the provision of such a carriage which is useful for slicing small pieces of material and which may be adjusted into position for slicing larger pieces of material. Another object is the provision of such a carriage which shall at one adjustment provide a V-shaped trough to support the material to be sliced and at another adjustment shall present an extended generally plane and horizontal supporting surface. Other objects will appear from time to time in the course of the specification and claims.

25 I illustrate my invention more or less diagrammatically in the accompanying drawings, wherein—

Figure 1 is a side elevation of my device;

Figure 2 is a plan view with parts broken away; and

Figure 3 is a section on the line 3—3 of Figure 1.

Like parts are indicated by like symbols throughout the specification and drawings.

35 Referring to the drawings A indicates any suitable base member for my slicing machine, with the ground engaging studs A¹. A² is any suitable housing member upwardly projecting therefrom with the face plate A³ associated with forward portion thereof and arcuately cut away as at A⁴ to expose the portion of the periphery of the knife B. It will be understood that any means may be employed for rotating the 40 knife and, as such means do not form part of the present invention they are not herein indicated. In order to bring the edge of the knife into the plane of the face plate and of the later described gauge plate I prefer 45 to tilt its axis slightly from perpendicularity to the face plate A³, the edge of the face

plate penetrating a depression B¹ formed in the face of the knife.

C indicates any suitable gauge plate which may be adjusted for example by rotation of the knob C¹ through mechanism which forms no part of the present invention and is therefore not illustrated.

D indicates a guide track or rod mounted at its ends on the supports D¹ and herein shown as overlying the secondary guide track D².

E generally indicates a carriage slidable along the rod D and, in the form herein shown, rotatable thereabout. It is provided with a downward extension E¹ which engages the track D² and thus prevents rotation of the carriage about the track D. E² are yielding buffers at the opposite ends of the carriage and E³ a handle for its manual actuation.

G generally indicates a supporting member or trough having one narrow side G¹ and a wide side G² herein shown as substantially at right angles thereto. The member G is provided with a lug or lugs G³ through which passes any suitable pivot rod or member G⁴ which in turn passes through corresponding lugs G⁵ on the carriage. G⁶ is an adjusting segment slotted as at G⁷ the slot being penetrated by any suitable locking member G⁸ herein shown as controlled by the manual knob G⁹. The size of the member G⁶ and the length of the slot G⁷ are such that when the member G is rotated into the 75 position in which it is shown in Figure 1 it presents a V-shaped trough adaptable for the slicing of relatively small articles.

When the knob G⁹ is rotated to release the adjusting segment G⁶, the member G can 80 be rotated into lower position, with its side G² then lying in a generally horizontal plane. When in such position larger articles may be deposited thereupon. For example it may then be employed to trim the 85 rind from pieces of bacon or to cut the crust from bread, sandwich loaves and the like. In order to prevent any possible slipping of the supporting member G in any adjusted position, the member G⁶ may be provided 90 with a plurality of notches G¹², one or more of which may be in engagement with one or

more correspondingly shaped opposed projections G^4 , integral with the boss or bearing member G^5 on the carriage E.

I also provide a pusher plate indicated as 5 H which is provided with the handle H^1 . Laterally extending from said handle are the arms H^2 to which are secured the guide pins H^3 which penetrate apertures H^4 in the lugs H^5 extending downwardly from the 10 members G^1 and G^2 respectively. It will be observed that this pusher plate is fully operative at all positions of the member G.

It will be realized that whereas I have described and shown a practical and operative device, nevertheless many changes might be made in the size, shape, number and disposition of parts without departing from the spirit of my invention. I therefore wish my description and drawings to 20 be taken as in a broad sense illustrative and diagrammatic rather than as limiting me to my specific showing.

I claim:

1. In a slicing machine having a rotary 25 knife and means for driving it, a carriage and means for guiding it across the face of said knife, and a work support pivoted upon said carriage for rotation about an axis at right angles to the path of movement of the 30 carriage.

2. In a slicing machine having a rotary knife and means for driving it, a carriage and means for guiding it across the face of said knife, and a work support pivoted upon 35 said carriage for rotation about an axis at right angles to the path of movement of the carriage, and means for adjusting it and for locking it at adjusted position.

3. In a slicing machine having a rotary 40 knife and means for driving it, a carriage and means for guiding it across the face of said knife, and a work support pivoted upon said carriage, and means for adjusting it and for locking it at adjusted position, including 45 a slotted adjusting segment interposed between said work support and the carriage and locking means associated therewith.

4. In a slicing machine having a rotary 50 knife and means for driving it, a carriage and means for guiding it across the face of said knife, and a work support pivoted upon said carriage, for rotation about a horizontal axis at right angles to the path of movement of the carriage.

5. In a slicing machine having a rotary 55 knife and means for driving it, a carriage and means for guiding it across the face of said knife, and a work support pivoted upon said carriage, for rotation about a horizontal 60 axis, generally perpendicular to the face of the knife.

6. In a slicing machine having a rotary 65 knife and means for driving it, a carriage and means for guiding it across the face of said knife, and a work support pivoted upon

said carriage, for rotation about a horizontal axis, generally perpendicular to the face of the knife, and means for adjusting it and for locking it at adjusted position.

7. In a slicing machine having a rotary 70 knife and means for driving it, a carriage and means for guiding it across the face of said knife, and a work support pivoted upon said carriage for rotation about an axis at right angles to the path of movement of the 75 carriage, said support including two supporting members lying substantially at right angles to each other.

8. In a slicing machine having a rotary 80 knife and means for driving it, a carriage and means for guiding it across the face of said knife, and a work support pivoted upon said carriage for rotation about an axis at right angles to the path of movement of the carriage, said support including two supporting members 85 having a fixed angular relation to each other.

9. In a slicing machine having a rotary 90 knife and means for driving it, a carriage and means for guiding it across the face of said knife, and a work support pivoted upon said carriage, said support including two supporting members having a fixed angular relation to each other, and of unequal lateral 95 extension.

10. In a slicing machine having a rotary 100 knife and means for driving it, a carriage and means for guiding it across the face of said knife, and a work support pivoted upon said carriage, said support including two supporting members having a fixed angular 105 relation to each other, and of unequal lateral extension, and locking means interposed between the supporting member of greater lateral extension than the carriage.

11. In a slicing machine having a rotary 110 knife and means for driving it, a carriage and means for guiding it across the face of said knife, and a work support pivoted upon said carriage, said support including two 115 supporting members having a fixed angular relation to each other and of unequal lateral extension, and locking means interposed between the supporting member of greater lateral extension than the carriage, including a slotted adjusting segment therebetween and locking means associated therewith.

12. In a slicing machine having a rotary 120 knife and means for driving it, a carriage and means for guiding it across the face of said knife, and a work support pivoted upon said carriage, said support including two supporting members lying substantially at right angles to each other, and a slotted adjusting segment interposed between said 125 work support and the carriage and locking means associated therewith.

13. In a slicing machine having a rotary 130 knife and means for driving it, a carriage and means for guiding it across the face of

said knife, and a work support pivoted upon said carriage, and a pusher plate mounted upon said work support.

14. In a slicing machine having a rotary knife and means for driving it, a carriage and means for guiding it across the face of said knife, and a work support pivoted upon said carriage, and a pusher plate

mounted upon said work support, and operative at all positions of adjustment of said support.

Signed at Indianapolis, county of Marion and State of Indiana, this 2nd day of March, 1928.

WILLIAM J. CAMPBELL.
